DISPENSER FOR PAPER CUPS

Walter E. Amberg, Beverly Shores, Ind., assignor
to Universal Paper Products Company, a cor-
poration of Illinois

Application August 23, 1944, Serial No. 550,710

2 Claims. (Cl. 206—56)

1

This invention relates to dispenser for paper cups and more particularly to containers for dispensing flat folded paper cups or like articles.

One of the objects of the invention is to provide a dispenser having a straight dispensing slot therein of less width than that of a cup to be dispensed to minimize the possibility of accidentally withdrawing cups from the dispenser.

Another object is to provide a dispenser in which flat paper cups or like articles are dispensed in bent or curved form.

Still another object of the invention is to provide a dispensing container which can be used both as a shipping container for the cups and as a dispenser from which the cups may be withdrawn one at a time.

The above and other objects and advantages of the invention will be more readily apparent from the following description when read in connection with the accompanying drawing, in which—

Figure 1 is a perspective view of a dispensing container embodying the invention;

Figure 2 is a view similar to Figure 1 illustrating a cup partially withdrawn from the container;

Figure 3 is a front elevation of the container;

Figure 4 is a plan view of a cup;

Figure 5 is a bottom view of a container;

Figures 6 and 7 are partial sections on the lines 6—6 and 7—7 respectively of Figure 2;

Figure 8 is a partial section on the line 8—8 of Figure 7; and

Figure 9 is a partial vertical section at right angles to Figures 6 and 7.

The container of the present invention is particularly adapted to carry and dispense cups of the type shown at 10 in Figure 4 of generally truncated wedge shape having a narrow end 11 and a portion of maximum width indicated at 12. Cups of this general type are formed by folding sheets of paper to the shape indicated and cementing the edges together. Such cups are dispensed flat and are opened by pressing the portion of maximum width transversely to spread the sides apart.

The container may be a temporary container of cardboard or the like or may, if desired, be a permanent dispenser formed of sheet metal. According to the present invention the container can satisfactorily be made of light materials such as cardboard and can serve both as a shipping container and as a dispenser for the cups. The container as seen in Figure 5 is of generally truncated wedge shape having a narrow truncated side

2

at 13 adjacent angular sides at 14 and a base side at 15. Preferably the base 15 is connected to the angular sides 14 by short parallel sides 16. In using the container as a dispenser it may be fastened to a wall or the like by fastening projections 17 on the side 15.

The upper end of the container is closed by a top sheet 18 which may be formed by folding over the sides overlying which is a raised portion 19 formed by folded parts of the sheet to improve the appearance of the container. The lower end of the container is closed by an angular bottom sheet 21 the sides of which are curved as indicated at 22 and taper inwardly toward the bottom of the sheet. The forward edge of the sheet 21 terminates short of the truncated side 13 as indicated at 23 to form a dispensing slot extending transversely across the truncated side of the container. The forward edge of the sheet 21 may also be formed with an open notch or groove 24 to facilitate removal of the cups as will appear hereinafter.

The truncated side of the container is of substantially the same width as the narrow edge 11 of the cups to be dispensed and is narrower than the maximum width of the cups at the point 12. In order to accommodate the edge portions of the cups when they are being dispensed, slot extensions 25 are formed in angular sides 14 of the container extending at acute angles from the opposite ends of the dispensing slot.

In use cups are stacked in the container which is of such size and shape as to hold the cups loosely so that they may drop toward the container bottom 21. The lowermost cups in the stack will have their sides bent by engagement with the inwardly tapered sides 22 of the container bottom as shown in Figures 6 and 7. To withdraw a cup from the container the forward edge of the lowermost cup may be grasped thru the notch 24 and pulled forwardly as shown in Figures 2 and 9. The side edge portions of the cup at its point of maximum width will pass throughout slot extensions 25 with the cup curved so that it may easily be withdrawn from the container. At the same time the necessity of curving or bending the cups prevents accidental withdrawal of more than one cup.

With the construction as illustrated and described, the container can easily be made of cardboard or like material to serve as a shipping container and as a dispenser for the cups. With this construction the cups will be held within the container and protected during shipment and handling and can easily be dispensed therefrom,

3

one cup at a time, when desired. It will be understood that for shipment and handling the dispensing slot and the slot extensions may be covered by sealing tape which can be easily removed when the dispenser is to be put in service.

While one embodiment of the invention is shown and described in detail, herein, it will be understood that this is illustrative only and is not intended as a definition of the scope of the invention, reference being had for this purpose to the appended claims.

What is claimed is:

1. A dispenser for flat paper cups and the like which are substantially truncated wedge shaped in outline comprising a container substantially in the shape of a truncated wedge in cross section and having side walls, a forwardly and downwardly sloping bottom wall, and a front truncated wall adapted to hold a stack of flat cups, the front truncated side of the container being formed adjacent the bottom wall with a slot extending transversely thereacross in the plane of the forwardly and downwardly sloping bottom wall, and the side walls of the container being formed with end extensions of said slot and extending up- 25

wardly at an angle with respect to said plane of the bottom wall whereby a cup withdrawn through the slot and extensions will be bent.

2. A dispenser for flat paper cups and the like which are substantially truncated wedge shaped in outline comprising a container substantially in the shape of a truncated wedge in cross section and having straight side walls, a bottom wall, and a straight front truncated wall adapted to hold a stack of flat cups, the side walls of the container adjacent the bottom tapering inwardly to the bottom wall to bend the sides of an adjacent cup, the front truncated side of the container being formed adjacent the bottom wall with a slot extending transversely thereacross in the plane of the bottom wall, and the side walls of the container being formed with curved end extensions of said slot and extending upwardly at an angle with respect to said plane and intersecting the juncture between the straight and tapered portions of the side walls whereby a cup withdrawn through the slot and extensions will be bent.

WALTER E. AMBERG.
